CLAIM

The ornamental design for a display screen with icon, as shown and described.

DESCRIPTION

The file of this patent contains at least one drawing executed in color. Copies of this patent with color drawing(s) will be provided by the Office upon request and payment of the necessary fee.

FIG. 1 is a front view of a display screen with icon showing a first embodiment of the claimed design;

FIG. 2 is a front view of a display screen with icon showing a second embodiment of the claimed design;

FIG. 3 is a front view of a display screen with icon showing a third embodiment of the claimed design; and,

FIG. 4 is a front view of the claimed design of FIG. 3 with additional broken line subject matter.

The broken lines of uneven length show the display screen and form no part of the claimed design.
